United States Patent Office.

GEORGE W. WAITT, OF PHILADELPHIA, PENNSYLVANIA.

Design No. 3,054, dated May 26, 1868.

DESIGN FOR A TRADE-MARK.

The Schedule referred to in these Letters Patent and making part of the same.

TO ALL WHOM IT MAY CONCERN:

Be it known that I, GEORGE W. WAITT, of the city of Philadelphia, in the State of Pennsylvania, have invented or produced a new and original Design for a Trade-Mark; and I do hereby declare that the following is a full, clear, and exact description of the same, reference being had to the accompanying drawing, making a part of this specification, and to the letters of reference marked thereon.

My design for a trade-mark consists of the representation of an unhulled cocoa-nut, surrounded by the letter C, as shown.

Referring to the drawing, A is the unhulled cocoa-nut, and B the surrounding letter C.

What I claim as my invention, and desire to secure by Letters Patent, is—

The design for a trade-mark herein shown and described.
